UNITED STATES PATENT OFFICE.

JOHN H. MILLER, OF BRIDGEPORT, CONNECTICUT, ASSIGNOR OF ONE-HALF TO JOHN L. CARPENTER, OF BRIDGEPORT, CONNECTICUT.

INDICATING ELECTRIC FUSE-PLUG.

1,101,946.

Specification of Letters Patent. Patented June 30, 1914.

Application filed April 4, 1912. Serial No. 688,549.

To all whom it may concern:

Be it known that I, JOHN H. MILLER, citizen of the United States, and resident of Bridgeport, in the county of Fairfield and 5 State of Connecticut, have invented certain new and useful Improvements in Indicating Electric Fuse-Plugs, of which the following is a specification.

This invention relates to inclosed electric 10 fuses of the plug type, such as are used in electric lighting circuits.

It is the object of the invention to provide means for indicating the condition of the fuse plug at all times so as to ascertain readily whether or not the same has been blown, 15 said means being so located as to be visible without the necessity of removing the fuse from its socket or of disconnecting any part of the plug; and particularly to provide an 20 external disk or label for the plug, which is so arranged as to be punctured and destroyed by the blowing of the fuse, and to be projected outward in a way to form an extended portion that may be readily detected by day 25 or night.

To the above end the indicating means is designed to be operated by the burning of the fuse and the expanding gases produced by the burning of the fuse, and is so arranged as to indicate upon the surface of the plug when the fuse is blown. This 30 indicating means is outside where it can readily be seen by day, and examined by night, without the aid of a light, by simply 35 feeling over the end of the plug, to determine whether or not the label is broken and the movable indicating member is projected outward from the body of the plug.

With these and other objects in view the 40 invention consists in the construction and novel combination and arrangement of parts hereinafter fully described, illustrated in the accompanying drawings, and pointed out in 45 the claims hereto appended, it being understood that various changes in the form, proportion, size and minor details of construction within the scope of the claims may be resorted to without departure from the 50 spirit or sacrificing any of the advantages of the invention.

Similar characters of reference denote like or corresponding parts throughout the several figures of the accompanying drawings,

forming a part of this specification, and 55 upon which—

Figure 1 shows a central vertical longitudinal section through my improved electric fuse plug complete; Fig. 2 is an inner end view of the main body member of the plug; 60 Fig. 3 is a similar inner end view of the flanged end member for inclosing the said body; Fig. 4 shows a disconnected perspective view of the fuse, screw, washer and terminal plate, shown assembled in Fig. 1; 65 Fig. 5 is a detached perspective view of the movable member, that is operated by the burning of the fuse; Fig. 6 is a longitudinal section of the sheet metal screw shell; Fig. 7 shows a detached perspective view of the 70 spring shown in Fig. 1 for actuating the indicating pin.

Referring in detail to the characters of reference marked upon the drawings, 10 indicates the main member or body of the plug 75 which is preferably formed of porcelain, and as will be seen has an opening therethrough, the inner portion 12 of said opening being larger than the outer end 11, to form an inclosed chamber. The outer end of the body 80 member is enlarged as shown, while the reduced peripheral portion is threaded to receive a correspondingly threaded shell 13 that serves to hold the several parts of the plug in place when assembled. The threads 85 of this shell also serve to allow the plug to be screwed into a base or socket (not shown). An end member 14 which is also formed of porcelain is fitted into the open end of the 90 large chamber 12 and is provided with an annular flange 15 that fits against the annular end of the body member. A lug 15^a upon the outer face of this end member 15 engages a pocket 10^a in the inner edge of the main member 10 to prevent the parts from 95 turning with respect to each other when the shell is attached. The outer end of the shell is provided with an inwardly turned flange 16 to engage the outer side of the flange 15 in a manner to securely hold the same and 100 end member up in place within the body member, when the shell is screwed on to the peripheral threads of the body member. This shell is originally formed in the shape shown in Fig. 6, with its inner edge 17 disposed 105 forward, and is thus run onto the plug, and flanged end member, to secure the two together, after which the said inner edge por-

tion 17 of the shell is spun down against the side of the last thread, as shown in Fig. 1, to prevent the shell from being turned off.

As shown in Fig. 1, I employ a movable indicating pin 18, having a pointed end 19, which is normally located in the reduced end 11 of the body member, and a head 20, fitted to operate like a piston in the larger bore of the body. A fiber washer 20^a is fitted upon the pin and against the head so as to form a close fit within the chamber 12. The top side of this piston or head is normally seated against the end of the above mentioned end member 14, and is free to be forced out by a spring 33 when released by the burning of the fuse within the end member, and thereby cause the pointed end of the pin to puncture the paper seal, or label 21 shown in this figure as being pasted on the end of the body and over the hole in which the said pin operates, thus leaving the seal broken and the pointed end of the pin projecting well through the hole in the end of the body member.

The spring 33 shown in Figs. 1 and 7 is bent into loop form and its end portion 34 is thus held by a small washer 35 made of suitable soft metal that is designed to be melted at the proper time by the heat from the fuse. This spring is transversely seated in suitable notches 36—36 in inner end of part 14, and so that the spring will be situated opposite the center of the head of the pin. It will also be noted that the end portion 34 of the spring which is to be released, is that which is located adjacent to the head of the pin so that when released by the melting of the washer, it will strike the head and drive the pin forward and out through the cap 21.

The fuse is preferably formed of round wire having the two end portions 23 and 24 flattened more or less as shown in Fig. 4. The outer end 23 of this fuse is secured between the flange 16 of the above mentioned shell and the notch periphery of end member 14, to form both an electrical and mechanical connection with the said shell. The body of the fuse is extended back through the longitudinal groove 25, inside of the body 10 of the plug and is then passed in through a notch 26 in end of member 14. The intermediate portion 22 is bent over the spring 33 and extended into the bore of the end member 14. The flattened end 24 of the fuse is bent around and extended through the slot 27 of washer 28, contained within the inner end of the end member. This washer is engaged by a screw 29 or rivet that passes through a central hole of the head of the end member, and engages a plate 30 arranged on the outer end of the head of the end member to form the central contacting point or terminal for the fuse. This plate 30 is provided with two

inturned points 31 that engage small holes in the head of the end member to prevent the plate from turning when assembled. The intermediate portion 22 of the fuse, that passes over the spring is designed to be the weakest point in the fuse, and, consequently, is where it burns across, causing an expansion of gases that forces the pin out through the paper cap. This part of the fuse is obviously situated within the end member, and is thus completely inclosed. The force of the combustion within the chamber in this instance, has its effect upon the piston, forming one end wall of said chamber, and drives it and the pin out, the latter being forced through the seal, while the piston stops against the inner end wall of the body. It will thus be seen that the indicating pin 18 may either be actuated by the spring when released, as explained, or by the expansion of the gases caused by the burning of the fuse, or by both said spring and gases, according to the particular reason which caused the fuse to burn across or heat as the case may be. The burning of the fuse is usually caused by heavy overload or short circuit and is quick, causing a sudden puff or expansion of the gases sufficient to cause the pin to shoot out, and in which case the spring may not be released. On the other hand, if the fuse becomes gradually overheated, due to different conditions, it in turn will heat the washer 35 in a way to melt the same and release the spring as heretofore described.

From the foregoing it will be seen that I have produced a simple and desirable form of construction, which can be inexpensively manufactured. The fuse which ordinarily has to be soldered to one or the other terminals, can, in this instance, be readily assembled and electrically connected with comparatively little expense. It will also be noted that the present trouble and expense due to loss by breaking the porcelains is also greatly lessened by reason of the fact that the assembled plug does not have to be put into a press for securing the parts together.

Having thus described my invention, what I claim and desire to secure by Letters Patent is:

1. An inclosed electric fuse plug, comprising a chambered body, a movable member mounted within the chamber of the body and having a projecting indicating means, a spring within the chamber to engage and operate the movable member, a fusible metal member that engages the spring, a fuse mounted within the body and engaging the fusible metal and adapted to melt the same and release the spring with the burning of the fuse.

2. An inclosed electric fuse plug, comprising a chambered body, a removable end

member mounted therein, a fuse mounted within the end member and having two external terminals, a slideable indicator piston mounted within the chamber, a spring with- 5 in the chamber that engages with and for operating the indicator piston, a link of soft metal engaging and for normally holding the spring and indicator, and connected with the fuse to be melted to release the spring 10 by the burning of the fuse.

3. An electric fuse plug, comprising a chambered body having an outlet hole there- through, an end insulating member fitted in and against the body, a screw shell attached 15 to the body and engaging and supporting the end member, a fuse one end of which is connected with the said shell and the other to a contact carried by the end member, a movable indicator member mounted 20 within the body, a spring mounted in the body adjacent to and for operating the indicator, but engaged and normally held against action by the said fuse.

4. An inclosed electric fuse plug, com- 25 prising a body having an opening there- through, an end insulating member fitted in against the body, a screw shell covering the body and to hold the end member in position, a terminal mounted within the end 30 member, a fuse one end of which is connect- ed to the said terminal and the other with the shell, a spring mounted within the end member adjacent to and adapted to operate the movable indicating member, means for 35 engaging and normally holding said spring in a contracted position, but adapted to be effected to release the spring by the burn- ing of the fuse connecting the two said terminals.

40 5. An electric fuse plug, comprising a chambered body with an outlet hole there- through, an insulating end member fitted in and against the said chambered body and having suitable slots therein, a screw shell 45 attached to the body and covering the end insulating member to support the same, a loop spring mounted within the slots of the end member, a fuse carried by the said end member and passing through the said 50 slot and engaging the spring in a way to normally hold the same, external terminals with which the ends of the fuse are connect- ed, a movable indicating member mounted within the chamber and recess of the body 55 adjacent to and adapted to be operated by the spring when released.

6. An inclosed electric fuse plug, com- prising a body having an opening there- through including an enlarged chamber, an 60 end member fitted in the chamber, a screw shell covering the body and end member,

and a movable indicator within the body, means to operate the indicator, a link of soft metal engaging and for normally holding the indicator operating means, a fuse 65 connected with the link in a way to melt the fuse when heated and to release the operating means to project the indicator from the body.

7. An inclosed electric fuse plug, com- 70 prising a body having an opening there- through including an enlarged chamber, an end member in the chamber, a screw shell covering the body and end member, a terminal on the end member, a fuse connecting 75 the terminal and shell and passing through the end member, a slideable indicating pin within the chamber and opening of the body and adapted to be projected through the end thereof, and means engaged by the fuse 80 to project the movable member from the body by the burning of the fuse.

8. An inclosed electric fuse plug, com- 85 prising a body having an opening there- through including an enlarged chamber, an insulating end member within the opening, a terminal on the end member, a terminal on the body, a fuse connecting the two terminals and passing through the end member, 90 a slideable indicating pin normally within the opening of the body, but adapted to be projected therefrom, and means engaged by the fuse to operate the movable member and extend it from the body by the burning of 95 the fuse.

9. An indicating electric fuse plug, com- 100 prising a body having a chamber therein, a pin mounted in the chamber of the body, but adapted to be shoved out and projected from the body, a spring within the body to engage and operate the pin, means for nor- mally holding the spring away from the pin, a fuse that engages the holding means, but adapted to burn and to release the 105 spring.

10. An electric fuse plug, comprising a body, a loop spring within the body, a link of soft metal connecting the free and compressed ends of the spring, a movable indicator adjacent to the spring to be operated 110 thereby, a fuse in engagement with the link to melt the same and release the spring with the burning of the fuse.

Signed at Bridgeport in the county of Fairfield and State of Connecticut this 30th 115 day of March A. D. 1912.
